TRAFFIC CONTROL SYSTEM

John L. Barker, White Plains, N. Y., assignor to
 Automatic Signal Corporation, East Norwalk,
 Conn., a corporation of Delaware

Application February 4, 1937, Serial No. 124,074

14 Claims. (Cl. 177—337)

The invention disclosed herein relates to traffic control apparatus and more particularly to apparatus of the traffic actuated type and has for its general purpose the provision of an apparatus adapted to control with a maximum of expediency and without conflict the flow of traffic thru an intersection where several traffic lanes meet or cross.

This system is of the traffic controlled type and the particular embodiment shown in the accompanying drawings is adapted to be used at the intersection of four traffic lanes, three mutually interfering and a fourth lane from which traffic would interfere with one of the three mutually interfering lanes but not with the other two.

It is entirely feasible to apply the principles disclosed in this embodiment to intersections of more than three mutually conflicting lanes by adding duplications of parts of the apparatus shown herein. Hence this disclosure, although applied herein to a specific type of intersection, is not restricted thereby to any one type of intersection.

It is an object of this invention to provide an improved form of traffic actuated apparatus by means of which traffic will be expeditiously and automatically handled so that a maximum traffic flow thru the common intersection of more than two lanes may occur without danger of conflict.

It is an object of this invention to provide traffic actuated apparatus of an improved type adapted to control, with a maximum of efficiency and safety, the traffic at an intersection where more than two lanes meet and adapted to display a go signal successively in each lane in response to traffic and at the same time to display a stop signal in other lanes from which traffic would conflict with that entering the intersection from the lane or lanes wherein the said go signal is being displayed.

It is a further object to provide an improved form of traffic actuated control of the nature described and adapted to accord right of way periods successively to the several lanes in a predetermined order in response to traffic and adapted to omit the right of way period in a lane wherein there is no traffic.

It is another object of this invention to provide an improved form of apparatus of the nature described wherein the duration of each period timed by the apparatus can be individually and independently preadjusted without changing the duration of any other time period.

It is also an object of this invention to provide an improved form of traffic actuated control apparatus for use at intersections where more than two lanes meet and which has a go signal period for each lane divided into an initial fixed period followed by a period variable between minimum and maximum limits by traffic and which has a warning signal period prior to each transfer of the go signal from one lane to another with separate independent adjustment of the duration of all of these periods for each lane.

It is a further object to provide an improved form of traffic actuated control apparatus for use at an intersection where more than two lanes meet adapted to accord the right of way to the lanes in a predetermined order in response to traffic and including a mechanism for determining at the beginning of the warning signal period whether the right of way has been called to the lane next in said normal predetermined order or to the lane next beyond such lane in said order, and if the right of way has not been called to the first named lane and has been called to the second named lane to cause the right of way to be transferred to the second named lane instead of to the first.

It is another object of this invention to provide an apparatus of the type described in which during the whole of the warning signal display period in the lane from which the right of way is being transferred another warning signal is displayed in the lane or lanes to which the right of way is next to be accorded whether the last named lane is the next in the normal predetermined order of right of way transfer or the lane beyond.

It is another object to provide a traffic actuated control apparatus of the type described in which is included a switching mechanism adapted for cyclic operation to normally accord the right of way to the lanes in a predetermined order in response to traffic, such switching mechanism normally assuming at suitably timed intervals successive positions in each of which a different signal indication is displayed to traffic but adapted so that if there is no traffic in a lane it will, during the clearance period in the preceding lane, move at markedly shortened intervals and without any signal display change thru those positions wherein a preliminary warning signal and a go signal would normally be displayed in said lane and, at the end of such clearance period, move on into the position wherein the go signal is accorded to the lane beyond.

It is also an object of this invention to pro-

vide a traffic actuated control of the nature described including a mechanism which will operate at the beginning of the warning signal period if the right of way period is to be omitted 5 in the lane to which it would normally next be accorded, such mechanism being adapted to remain operated and to maintain the signal display unchanged until the end of such warning signal period at which time it will become deenergized 10 and permit the right of way to be accorded to the lane beyond and further adapted to prevent approaching traffic in the lane in which the right of way period is being omitted from interrupting such transfer but adapted to cause the right of 15 way to be given at the next normal opportunity to such approaching traffic in the lane in which the right of way period is being omitted.

It is a further object to provide a traffic actuated apparatus of the described type in which 20 the right of way is accorded to the lanes by a six position cyclic switching mechanism adapted to move into the six positions successively at suitably timed intervals but having apparatus associated therewith to time an additional period 25 in three of the six positions thus making available in each of these three positions two successive time intervals during which parts of the apparatus can be caused to perform different functions thereby causing the six position cyclic switching 30 mechanism to operate so as to give in effect a cycle of nine positions.

One embodiment of the invention will now be described with reference to the accompanying drawings, in which:

35 Figure 1 is a plan view of an intersection equipped with this apparatus showing the location of the traffic signals, traffic detectors, and the control mechanism. The several traffic flows or phases are designated by the letters A, B, 40 C and D.

Figures 2 and 3 jointly constitute a schematic circuit diagram of the control apparatus including connections with the traffic detectors and the traffic signals. The particular signal connections 45 shown in Figure 3 are arranged to provide a cautionary signal before the go signal as well as after the go signal in each lane.

Figure 4 shows an alternative arrangement of the signal relays to provide a cautionary signal in 50 each lane only after the go signal has been displayed therein.

The apparatus of this system accords the right of way to the various lanes in conformity with the requirements of traffic as indicated thru the 55 actuations of traffic detectors located in the several lanes. If traffic is present in all lanes the right of way is accorded to them in a predetermined order and for a time period in each lane determined by traffic. If there is no traffic on a 60 particular lane the apparatus will omit the right of way period on that lane and, without delay, accord the right of way to the next lane in the predetermined order in which traffic is present.

The apparatus is adapted to be adjusted so that 65 in the absence of traffic the right of way will normally revert from lane to lane in a predetermined order at predetermined intervals or, by a different adjustment, the right of way can be caused to normally revert to a particular lane 70 in the absence of traffic in the other lanes, or, by still another adjustment the right of way can be caused to remain on the lane to which it was last called until called by traffic to some other lane.

The go signal or right of way period in each 75 lane is divided into two parts, the first of which

is called the initial interval and is predetermined in time and is not affected by traffic actuations. The second portion of the go signal period can be extended by traffic actuations occurring during this part of the go period in the lane in which the go signal is being displayed. If traffic is continuous in the lane in which the go signal is being displayed and would therefore unduly extend the go signal period thereon, a cross lane "call", due either to waiting traffic or to adjustment 10 of the apparatus to normally revert to that lane, will cause this go signal period to be limited to a predetermined maximum.

This apparatus is also adapted to automatically cause the right of way to return to any lane 15 at the first reasonable opportunity if, when said right of way last left this lane a detector located therein had been actuated within a predetermined time.

This apparatus is preferably arranged to cause 20 a warning signal to be displayed for a predetermined period to traffic in the lane or lanes from which the right of way is about to be withdrawn and if desired another warning signal to be simultaneously displayed in the lane to which the 25 right of way is next to be granted in order to notify traffic therein that it is about to receive the go signal.

The control apparatus of which the circuit diagram is shown in Figs. 2 and 3, is of the type in 30 which cams, fixed on a shaft which is revolved in steps by a solenoid with a ratchet and pawl mechanism or other suitable means, operate contacts to control relays which in turn control the signal indications. Other contacts operated by 35 cams on this shaft cooperate with relay contacts to connect the various timer circuits properly for the particular part of the signal cycle prevailing.

The timing of all periods is accomplished thru 40 gas discharge tubes used in conjunction with condensers in which the variation of the charge is instrumental in measuring a time period. When the voltage on the condenser reaches the breakdown voltage of the tube to which it is connected the tube becomes conducting and causes the condenser to discharge thru a relay the operation of which terminates the period being timed and initiates action of the solenoid. In this embodiment of the apparatus all the time periods are independently adjustable so that different 45 periods applying to the same lane or corresponding periods applying to different lanes can be individually timed.

Traffic actuated apparatus for controlling traffic at intersections where more than two traffic 55 lanes cross has been in use for some time. One such apparatus is described in the British Patent #351,703.

The apparatus of the above British patent is arranged to show a warning signal in a lane when 60 the right of way is to be withdrawn therefrom but it does not show a warning signal immediately prior to the display of the go signal in the lane to which the right of way is next to be accorded.

Furthermore in the above apparatus corresponding time periods in different lanes must be 65 of the same magnitude since no provision is made for individual adjustments of these periods for each lane.

The embodiment of the invention shown in this 70 application is an adaptation of the cam shaft type of traffic actuated control requiring no electric motor and employing gas discharge tubes with plate condensers wherein the variation of 75

the charge at a suitable rate is instrumental in timing the several time periods. This type of control has proved eminently satisfactory and economical in controlling traffic at intersections where two traffic lanes cross.

In the present invention this same type of apparatus is adapted to control the flow of traffic at intersections where more than two traffic flows cross. The economy and timing flexibility inherent in the condenser-charging type of timing mechanism is by this invention made available for control of traffic where more than two traffic lanes intersect.

The apparatus of this invention has many new features including an improved mechanism for selecting the lane to which the right of way is to be transferred and this mechanism operates in such a way as to accord the right of way only to those lanes to which it has been called either by traffic actuation or by adjustment for normally reverting thereto in the absence of traffic.

In addition it has an improved form of rapid stepping mechanism which, during the warning signal display period, causes the cam shaft without signal changes to move rapidly thru intervening positions to the proper position preparatory to displaying the go signal in the lane selected by the selecting mechanism mentioned above.

Furthermore, the apparatus includes an improved mechanism adapted to display the warning signal concurrently in the lane from which the right of way is being withdrawn and in the lane to which the right of way is next to be accorded during the whole of a normal warning signal display period in the first mentioned lane. This feature makes the green, amber, red, amber, green signal sequence in each lane available for use at an intersection where more than two traffic flows cross.

However, the apparatus disclosed herein is not limited to the above mentioned signal sequence but can by a slight circuit change be adapted to provide any one of several other signal sequences.

Its adaptation to provide a green, amber, red, red, green signal sequence in each lane is shown in Fig. 4.

The signals for controlling traffic in phase D are connected in Figs. 3 and 4 to the phase C signals in such a way as to permit phase D traffic to move with both phase A and phase B.

By connecting the phase D signals in the same manner to the phase A signals instead of the phase C signals, phase D traffic can be given the right of way simultaneously with phases B and C instead of with phases A and B.

Or, by connecting the traffic phase D signal similarly to phase B signals, phase D traffic will be given the right of way concurrently with phases C and A.

In the particular type of intersection shown in Fig. 1 traffic flow D conflicts with flow C only. Therefore, the flow D signals are connected in Figs. 3 and 4 to the signals of phase C in order to give the traffic flow D the right of way while it is accorded to flow A or flow B.

The embodiment of the invention depicted in Figs. 1, 2 and 3, which, as mentioned, is adapted to provide the signal sequence green, amber, red, amber, green in each lane will first be described.

Referring to the details of Fig. 1, the lane from which traffic flow A moves is designated as "phase A", the lane from which traffic flow B moves is designated as "phase B", those from which traffic flow C moves are designated "phase

C", and the lane from which D moves is designated "phase D".

In Fig. 1 the signal "Sig." contains suitable green, yellow, and red lamps, lenses and/or reflectors or their equivalents for properly displaying indications of right of way, change of right of way and interruption of right of way respectively to each of the several traffic phases. The control apparatus labelled "Control Box" is located at the lower left corner of the figure and the traffic detectors M, N and P are shown in phases A, B and C respectively. Connecting wires are indicated between the signals, control box and the detectors.

It will be noted that no traffic detector is located in the phase D lane. Traffic flow D therefore has no means for calling or holding the right of way, such means being unnecessary since right of way is automatically accorded to phase D whenever it is accorded to phase A or B.

With reference to the traffic flows indicated in Fig. 1 it can be seen that the portion of phase B traffic which moves straight ahead crosses the path of phase A traffic and would cause interference if both flows moved simultaneously. It is also evident that traffic moving straight ahead out of phase C would cross both flow A and flow B. Hence traffic flows A, B and C are mutually interfering.

The traffic flowing straight ahead out of phase D on the other hand does not conflict with that flowing as indicated out of phase B and can obviously merge with that flowing out of phase A. However, the phase D traffic crosses phase C traffic. Thus it can be seen that phase D traffic interferes with phase C traffic but not with that from phases A or B. It is for this reason that phase D traffic can be allowed to flow simultaneously with that from phase A or phase B, but must be stopped when phase C is given the right of way.

A complete signal cycle during which right of way is accorded successively to the mutually interfering traffic flows A, B, and C, together with suitable warning or change signals displayed after each accord of right of way, requires six positions of the camshaft. In the present embodiment of the apparatus the camshaft is advanced from one position to the next by action of a solenoid. These movements of the camshaft may each be 50 of 60 degrees so that one revolution of the camshaft corresponds to one complete signal cycle, or the camshaft may be arranged to provide a number of cycles of the signals during one revolution in which case the camshaft is provided 55 with for example, 12 or 18 positions and each movement of the camshaft by the solenoid is thru a correspondingly smaller angle.

With the signals connected as shown in Fig. 3 the signals displayed in the several rest positions of the cam shaft are as follows:

When the cam shaft is in position 1 the go signal is normally displayed to traffic flows A and D and when the cam shaft is in position 2 the warning signal is normally displayed to traffic flow A and to the traffic flow which is next to be accorded the right of way.

When the cam shaft is in position 3 the go signal is normally displayed to traffic flows B and D and in cam shaft position 4 a warning signal 70 is normally displayed to traffic flow B and to the traffic flow which is next to be accorded the right of way. Similarly in cam shaft position 5 a go signal is normally displayed to traffic flow C and stop signals to traffic flows B, C, and D. In cam 75

- shaft position 6 a warning signal is normally displayed to traffic flow C and to the traffic flows which are next to be accorded the right of way one of which is invariably flow D.
- 5 From the above it can be seen that the go signal is shown to traffic flow D at all times except while the go signal or the warning signal is being displayed to traffic flow C.
- 10 There are two cases of transfer of right of way from a phase.
- Case 1.—If, while the right of way is accorded to one phase, either traffic or adjustment of the equipment for normal reversion calls for the right of way on the phase next in the normal order of progression, the right of way will be transferred thereto at the first break of predetermined time duration in the moving traffic, or, if no such break occurs, at the end of the predetermined maximum period.
- 15 Case 2.—If on the other hand, while the right of way is accorded to one phase, the right of way is called to a phase not normally next in the order of progression, and there is no call for the right of way on the intervening phase, the right of way will be transferred next to the calling phase, said transfer taking place at the first break of predetermined time duration in the moving traffic or if no such break occurs at the end of the predetermined maximum period.
- 20 Under the above conditions, when the go signal is extinguished and the warning signal is displayed in the phase from which the right of way is being yielded, the stop signal is extinguished and a warning signal is displayed to the phase to which the right of way is next to be accorded, in the first case to the phase next in the normal order of progression, and in the second case to the phase beyond that next in the normal order of progression.
- 25 If the right of way is to be transferred to the phase not next in the normal order of progression, the above named warning signals will remain continuously displayed while the cam shaft is stepped rapidly thru intervening positions until it comes to rest in the position immediately preceding that in which the go signal is displayed to the phase to which right of way is next to be accorded. During this cam shaft movement no signal changes occur in any phase.
- 30 The cam shaft will then remain in the above mentioned rest position for a normal warning signal period during which time the warning signals remain displayed as described.
- 35 At the end of the mentioned warning signal period the cam shaft will be advanced one more position by action of the warning signal period timer which will be described later, and the transfer of the right of way will be completed without any change of signal having occurred in the intervening phase wherein the stop signal was continually displayed.
- 40 If a traffic actuation occurs in the intervening phase while the right of way is being transferred as described above, such actuation will not interfere with the transfer described but will be effective to call the right of way to the intervening phase at the next opportunity.
- 45 The controller shown in Figs. 2 and 3 includes three timers. One, consisting of relay AS, tube 70 FA and condenser QA, times the initial interval of the go signal period in each phase. A different charging resistance for condenser QA in each phase permits the initial intervals to be of different lengths in the different phases.
- 50 Another timer, consisting of relay CS, tube FA and condenser QA employing the same condenser and tube as the initial interval timer but in which relay AS of the initial interval timer is replaced by relay CS, serves to time the vehicle intervals of the go signal period and the amber or warning signal period in each phase. The period of this timer is also independently adjustable in each interval which it times. When timing the vehicle interval portion of the go signal period this timer is subject to reset by traffic actuations in the lane wherein the go signal is being displayed.
- 55 A third timer, called the maximum timer, consisting of relay BS, tube FB and condenser QB, times a maximum period beyond which moving traffic in the go signal phase cannot hold the right of way against a call in another phase. The maximum period for each phase is independently adjustable. This timer is also provided with a special low resistance condenser charging circuit which is used to move the cam shaft rapidly thru the intervening positions when a phase is to be skipped under the circumstances previously described.
- 60 The maximum timer is so arranged that whenever the right of way has been called to any phase it will operate during all subsequent intervals until the right of way has been accorded to the phase to which it has been so called. This timer will therefore be effective to move the cam shaft into its next position at the end of a predetermined period, such period being long enough so that the maximum timer will not operate to do this until the period of the timer normally timing each such interval has expired, and the said timer normally timing such interval has therefore obviously failed to function in its usual manner.
- 65 Relays AD, BD and CD are responsive to actuations of the traffic detectors 10, 11, and 12, 40 located in the A, B and C phase lanes respectively. Each of these relays is effective to call the right of way to the phase with which it is associated when the detector in this phase is actuated during the warning or stop signal display period therein and each is effective to cooperate with the vehicle interval timer to prolong the go signal display period in the phase with which it is associated when operated by traffic during the vehicle interval portion of the 50 said go signal display period.
- 70 Switch 13 when closed causes relay AD to operate and lock-in over a holding circuit so as to call the right of way to phase A but the holding circuit for relay AD is opened at another 55 point during the vehicle interval portion of the phase A go signal period so that the energization of relay AD to extend the phase A go signal display period can be occasioned only by traffic actuations of the A phase detector as explained above. Switches 14 and 15 cooperate similarly with relays BD and CD respectively.
- 75 If all three of these switches are open the right of way will remain on the phase to which it was last called until a traffic actuation occurs in another phase. With only one of these switches closed the right of way will in the absence of traffic normally revert to the phase with which this switch is associated, thus giving an arterial system. With any two or all three of these 70 switches closed a reverting system will result in which the right of way, in the absence of traffic, will normally be accorded successively in a predetermined order to the phases with which the closed switches are associated. The right of way 75

under the reverting system will remain on each phase to which it is accorded for a minimum time period extendable to a maximum time period by traffic actuations.

- 5 If the go signal display period on phase A is terminated by operation of the maximum timer instead of by operation of the vehicle interval timer, so that the last vehicle which actuated the detector in phase A did not have a full vehicle interval in which to pass thru the intersection, a call for the return of right of way is automatically set up thru the operation of relay AD by the maximum timer when the latter operates.
- 10 Relays BD and CD are similarly operated to put in an automatic right of way return call to their respective phases if the right of way period is terminated therein thru the operation of the maximum timer.
- 15 If the right of way is called to a phase other than that normally next in the order of progression, as has been explained, the cam shaft is stepped rapidly and without signal display change thru the positions wherein the preliminary warning signal and the go signal would normally be displayed to the omitted phase. This effect is accomplished in accordance with the invention by the operation of relay J which is arranged so that when a phase is to be omitted, this relay
- 20 will be operated at the beginning of the warning signal period of the preceding phase and will be thereupon effective to energize the previously mentioned rapid stepping timing circuit associated with the maximum timer which will carry
- 25 the cam shaft quickly thru the intervening positions to its proper destination.

In addition to the above, relay J cooperates in selecting the phase to which the right of way is next to be accorded and causing a warning signal to be displayed therein simultaneously with that displayed in the phase from which the right of way is being withdrawn. The method by which this is accomplished will later be explained in detail.

45 The initial interval and the vehicle interval period of the go signal display period of each phase are timed in one cam shaft position, there being one such cam shaft position for each of the three mutually interfering phases. For example, both of the above mentioned portions of the phase A go signal period are timed while the cam shaft remains in position 1, those for phase B are timed while the cam shaft is in position 3 and those for phase C are timed while the cam shaft is in position 5.

55 At the end of each initial interval relay AS of the initial interval timer operates and deenergizes relay IV. The deenergization of relay IV causes circuit changes which terminate the initial interval and institute the succeeding vehicle interval period of the go signal period without changing the cam shaft position or signal display, all of which will be explained later in detail.

60 Relays AG, BG, CG, AY, BY, CY, AYX, BYX, and CYX are effective to control the signal display in the several phases and to properly connect some of the timing circuits therefor as will be explained later in the detailed description of the operation of the system thru a complete cycle of signal changes.

65 With traffic waiting on each phase the right of way, as previously mentioned, will be accorded to the three mutually interfering phases in the order, A, B, and C. Phase D, as before men-

tioned, is given the right of way except when it is accorded to phase C.

70 As the right of way is withdrawn from a phase there are, as previously explained, two possibilities. Either it will be accorded to the phase next in the normal order of progression or, if there is no right of way call thereon, it will skip this phase and be accorded to the one beyond. The condition of relay J indicates to which of these phases the right of way has been called and so determines which of these phases is to be accorded the right of way.

75 If there is a call for the right of way on the phase next in the normal order of progression, relay J will be in deenergized condition and the sequence of operations will be such that the right of way will be accorded to such next phase. If, on the other hand, there is no such call for the right of way to the phase next in the normal order of progression and there is a call for the right of way to be accorded to the phase beyond, relay J will be energized at the beginning of the warning signal period of the phase from which the right of way is being withdrawn. This operation of relay J will cause a different sequence of operations to occur and cause the right of way to be accorded to the phase beyond the one next in the normal order of progression.

80 In general, it can be said that relay J cooperates to accomplish these results as follows: Considering first the energizing circuit for relay J it can be seen that positive A. C. power is permanently supplied thru wire 16. Negative A. C. power on the other hand can be supplied thru three different circuits one of which will be completed during each warning signal period, if, and only if, the next phase in the normal order of progression is to be omitted.

85 Consider the particular circuit thru which relay J can be energized during the A phase warning signal period. This circuit starts at negative A. C. power and includes wire 17, back contact bd6 of relay BD, wire 18, contact ay5 of relay AY, wire 19, the coil of relay J and wire 16 which connects with positive A. C. power. Relay AY is always operated during the phase 40 warning signal period and only during this period. Therefore contact ay5 will be closed during each phase A warning signal period.

90 If the right of way is to be accorded to phase B relay BD will have been operated and contact bd6 of the above circuit, will consequently be open. Both of the other two circuits supplying negative power to relay J are open in the A phase warning signal period and since the above described circuit is open at contact bd6, it follows that when the right of way is leaving the A phase and going to the B phase, relay J will be deenergized. This fact, as will later be explained in detail, will cause the B phase warning signal to be energized with the A phase warning signal during the A phase warning signal period.

95 If the right of way had not been called to phase B relay BD would not be operated and contact bd6 of the above described relay J energizing circuit would be closed. Hence when at the beginning of the phase A warning signal period contact ay5 of relay AY is closed as previously mentioned, the described energizing circuit for relay J will be completed and relay J will operate.

100 As soon as relay J does so operate the closure of contact f2 will provide a by-pass around contact bd6 which will hold relay J energized during the phase A warning signal period even though

a phase B traffic actuation should operate relay BD and so open contact *bd6*. This prevents a phase B actuation, occurring during the transfer of the right of way from phase A to phase C, from interrupting said transfer after it is started.

With relay J operated the phase C and phase D warning signals instead of the phase B warning signal will be energized with the phase A warning signal during the phase A warning signal period. This will later be explained in detail. In addition to the above, the operation of relay J during the phase A warning signal period causes the special rapid timing circuit of the maximum timer to function to step the cam shaft rapidly thru phase B positions which will also later be explained in detail.

The circuit by which relay J can be energized during the phase A warning signal period has been described here in some detail. The other two mentioned similar circuits are effective under corresponding similar conditions to energize relay J during the phase B or the phase C warning signal periods wherein its functions are of the same nature as those described above in connection with the phase A warning signal period.

Operation of this embodiment of the invention in transferring the right of way thru a cycle from phase A to phase B then to phase C and then back to phase A will now be described. It will be remembered that phase D traffic is automatically accorded the right of way with phases A and B but not with phase C. Phase D traffic has no means for calling or holding the right of way and is therefore not a factor in controlling the transfer of the right of way. Hence it does not need to be considered in that respect.

The sequence of transfers given above omits no phase. Hence relay J will remain unoperated during the whole procedure. This being the case, it will be remembered that in this part of the description involving no phase omissions all make contacts of relay J will be continuously open and all back contacts will be continuously closed.

The condition of the cam shaft contacts in each position of the cam shaft is indicated in the table at the bottom of Fig. 3. In this table an X in a square indicates that the cam contact 50 whose number appears at the top of the column is closed when the cam shaft is in the position identified by the number at the end of the row in which the X occurs.

Assume that the right of way has just been accorded to the phase A and that traffic is moving thereon, while traffic waits on phases B and C. The cam shaft is in position 1. Relays AD, BD and CD will each have been energized by traffic actuation of the detectors in their respective phases. Relay BD energized by the circuit thru switch *11*, relay BD and lead *44* will continue to be energized by a holding circuit thru the relay and over armature *bd1* and cam contact *C18*; relay CD will remain energized by a similar holding circuit over armature *cd1* and cam contact *C13*. Relay AD will remain energized over armature *ad1*, lead *46*, armature *iv13*, and lead *45*.

The go signal is displayed to traffic on phases A and D whereas the stop signal is displayed to B and C phase traffic. The A phase go signal AGS is energized thru a circuit starting at positive A. C. power thence thru wire *20* to armature *ayx1* and contact *ayx3* of relay AYX, wire *21* to armature *ag1* and contact *ag2* of relay AG to A

phase go signal AGS thence to negative A. C. power.

Relay AG, which must be operated to complete the circuit described above, is energized in cam shaft positions 1 and 2 thru a circuit from negative A. C. power to contact *j9* of relay J, wire *22* to cam contact *C7* to the coil of relay AG thence to positive A. C. power.

The B phase stop signal BRS is energized from positive A. C. power thru wire *20* to armature *byx1* and contact *byx3* of relay BYX, wire *23* to armature *bg1* and contact *bg3* of relay BG, to the B phase stop signal BRS thence to A. C. negative power.

The C phase stop signal CRS is energized thru a circuit from A. C. positive power thru wire *20* to armature *cxy1* and contact *cxy3* of relay CYX, wire *24* to armature *cg1* and contact *cg3* of relay CG, to the phase C stop signal CRS, thence to negative A. C. power.

In Figure 3 the D phase go signal DGS, which is displayed except when C phase has the right of way, is energized thru the same circuit as the C phase stop signal, and the D phase stop signal DRS is energized by the same circuit as the C phase go signal.

As mentioned before, two successive periods are timed in cam shaft position 1, the first being the A phase initial interval. The initial interval timer includes tube FA, plate condenser QA and relay AS. While the cam shaft solenoid S was in its operated position preparatory to moving the cam shaft from position 6 to 1, solenoid contact *s1* was closed thereby discharging condenser QA thru the circuit from negative D. C. power thru wire *25* to contact *s1*, resistance RA, wire *26* to condenser QA thence thru wire *27* back to negative D. C. power. Therefore, when the cam shaft reaches position 1 there is substantially no charge in condenser QA.

The timing of the phase A initial interval is accomplished thru charging condenser QA from substantially zero voltage up to the break-down voltage of tube FA at a rate determined by the magnitude of resistance AI. The charging circuit which accomplishes this starts at D. C. plus power thence thru variable resistance AI to contact *iv5* and armature *iv10* of relay IV, contact *C2*, wire *26* to condenser QA thence thru wire *27* to D. C. negative power. The timing of the A phase initial interval is adjustable by changing the value of variable resistance AI.

The charging circuit just described included contact *iv5* and armature *iv10* of relay IV, hence, a discussion of the energizing circuit for relay IV is included at this point.

Relay IV is energized as the solenoid is energized preparatory to removing the cam shaft into positions 2, 4 and 6 thru the circuit from A. C. plus power to the coil of relay IV, wire *28* to contact *s3* paralleled by contact *C21*, and thence to A. C. negative power. This operating circuit is rendered incomplete by the opening of contact *C21* and solenoid contact *s3* in cam shaft positions 1, 3 and 5, contact *s3* being closed only while the solenoid is energized. However relay IV has a holding circuit from positive A. C. power thru the coil of relay IV, contact *iv1* of relay IV, wire *29* to back contact *as3* of relay AS and thence to A. C. negative power.

Relay IV, after each energization as described above, will be kept energized by this holding circuit until the end of the next subsequent initial interval at which time, its above described operating circuit being open at contacts *s3* and *75*

C21, it will be released thru the opening of its holding circuit at contact *as3* of relay AS, the initial interval timer relay. Thus it can be seen that the operating circuit and the holding circuit 5 of relay IV cooperate to keep this relay energized at all times except during the vehicle interval of each go signal period during which period relay IV is invariably deenergized. Contacts of relay IV included in the previously described initial interval timer charging circuit will therefore 10 be effective to complete the circuit as mentioned.

As mentioned before, during the initial interval of the phase A go signal period, condenser QA of the initial interval timer is being charged at a 15 predetermined rate to time this period. When the voltage of condenser QA reaches the breakdown voltage of tube FA this tube will become conducting and condenser QA will thereupon discharge thru the coil of relay AS which relay will then 20 operate.

The discharge circuit for condenser QA thru relay AS starts at negative D. C. power thence thru condenser QA, wires 26 and 30 to tube FA, armature *iv16* and contact *iv2* of relay IV, to contact C31, wire 31 to coil of relay AS thence back to negative D. C. power. The operation of relay AS does not cause the cam shaft to be moved but as previously pointed out it does deenergize relay IV by opening its holding circuit at contact *as3*. 25

30 The closure of contact *as1* of relay AS completes an auxiliary discharge circuit for condenser QA thru coil of relay AS and resistance RA. The completion of this direct discharge circuit insures that, although its previously described normal 35 energizing circuit is opened upon the deenergization of relay IV, relay AS will remain operated until the voltage of condenser QA has been decreased to less than that required to hold relay AS operated.

40 The operation of relay AS also opens contact *as2* in the relay CS coil circuit and keeps this circuit open until relay AS assumes its unoperated condition, i. e., until the voltage of condenser QA has been lowered to such a degree that it would 45 be ineffective to operate relay CS if connected to it.

The above arrangement assures that when relay AS is energized with the consequent deenergization of relay IV, the energy remaining in condenser QA at that time will not be passed thru relay CS. This prevents the operation of relay CS at the end of the initial interval of the go signal period. When the energy in condenser QA has been drained to a low level, relay AS will be 50 55 energized and its temporary auxiliary circuit will be opened at contact *as1*, and the normal circuit thru which relay CS is later to be energized will be restored by closure of contact *as2*.

The deenergization of relay IV at the end of the 60 phase A initial interval has three effects. It deenergizes relay AD through opening its holding circuit at contact *iv13*, contact C15 of this circuit being open in cam shaft position 1. The relay AD operating circuit is independent of this holding circuit so relay AD continues to be responsive to A phase detector actuations to extend the go signal display period during the following vehicle interval portion of the A phase go signal display period.

70 Furthermore, the deenergization of relay IV opens the circuit previously traced from tube FA to the coil of relay AS by separating armature *iv16* from contact *iv2* of relay IV and at the same time prepares the circuit to the coil of 75 relay CS from tube FA through the engaging of

armature *iv16* with contact *iv3* of relay IV, which circuit will be completed upon the closure of contact *as2* as previously described. Another armature of relay IV, *iv10*, substantially simultaneously separates from contact *iv5* and engages contact *iv4* thus substituting variable resistance AV for variable resistance AI in the charging circuit for condenser QA, and also making condenser QA subject to discharge thru contact *ad3* of relay AD upon actuation of the A phase detector. 5 10

As a result of these described circuit changes caused by the deenergization of relay IV a timer circuit is set up to time the vehicle interval position of the A phase go signal display period, which timer includes condenser QA, charging resistance 15 AV, tube FA and relay CS. The charging circuit for condenser QA in this timer is the same as that described for the initial interval except that positive D. C., is supplied to armature *iv10* of relay IV thru contact *iv4* and resistance AV instead of 20 contact *iv5* and resistance AI.

Furthermore a discharge path for condenser QA is added at contact *iv4* thru cam contact C1, wire 32 and contact *ad3* of relay AD thence to negative D. C. power. This discharge path is 25 completed upon each traffic actuation of the A phase detector, thru the energization thereby of relay AD and the consequent closure of contact *ad3*. This operation is the means by which A phase traffic extends the A phase go signal period 30 during the vehicle interval portion of this period.

During the A phase vehicle interval period condenser QA is connected with tube FA and relay CS thru a circuit starting at negative D. C. power thence to condenser QA, thru wires 26 and 30 to 35 tube FA, to armature *iv16* and contact *iv3* of relay IV, wire 33 to contact *as2*, to coil of relay CS.

From the other side of relay CS coil there are four parallel paths any one of which will, if completed, permit condenser QA to discharge thru 40 the coil of relay CS when tube FA becomes conducting. One of these which includes wire 34 and contact C19 is completed by closure of contact C19 in cam shaft positions 2, 4, and 6, the warning signal display positions so that this timer 45 will be effective to time the warning signal display period as will be discussed later.

The other three of the four circuits are individually effective to prepare an operating circuit for relay CS which will be completed if tube FA 50 becomes conducting during the vehicle interval portion of a go signal period. Each of these three circuits includes in series a cam contact and a contact of one of the relays AD, BD, or CD, each of which relays will be energized if the right of 55 way has been called, either by traffic actuation or adjustment for normal reversion, to the phase with which it is associated.

While the go signal is displayed in a phase, the operation of the relay responsive to actuation of the traffic detector in that phase will be ineffective to complete the particular relay CS energizing circuit wherein its contact is included because the cam contact in each circuit is arranged to be open in the cam shaft position in 65 which the go signal is displayed in the said phase. However, an operating circuit for relay CS always will be prepared in each vehicle interval period provided the right of way has been called to a phase other than that in which the go signal is being displayed.

For example, during the A phase vehicle interval an actuation of a phase B or C detector will complete a circuit for operating relay CS, as follows; starting with coil of relay CS, wire 75

34, thence thru either contact *bd2* and cam contact *C17* or contact *cd2* and cam contact *C14*, depending upon whether the actuation was in phase B or phase C respectively.

5 The completing of either of the last two circuits will cause relay CS to be operable during the A phase vehicle interval when tube FA becomes conducting, i. e., when the last A phase vehicle has had sufficient time to pass thru the 10 intersection.

An actuation of an A phase detector during the A phase vehicle interval, which as previously mentioned will cause relay AD to operate, will not complete an operating circuit for relay CS 15 since the cam shaft contact *C16* is open in the A phase go signal cam shaft position. Such an actuation will however, discharge condenser QA thru the previously described discharge circuit to extend the A phase go signal display period.

20 When the right of way has been called to another phase and there is continuous traffic in the A phase which repeatedly resets the vehicle interval timer and so prevents this timer from acting, the right of way will at the end of a pre-determined period be transferred by action of the maximum timer.

If the equipment is adjusted to cause normal reversion of the right of way to either the B or C phase, or if traffic is waiting on either of these 30 phases at the beginning of the A phase go signal period the maximum timer will begin to time its period when the right of way is accorded to the A phase. If there is no traffic waiting in the B or C phase when the right of way is accorded to A phase and the equipment is not adjusted to automatically accord the right of way to either phase B or phase C, the maximum timer will not begin to time its predetermined period when the right of way is accorded to A phase but will 35 begin to time the maximum period when the next B or C phase traffic actuation occurs.

The maximum timer includes condenser QB, tube FB and relay BS. Condenser QB is charged thru a different variable resistance when timing 45 the maximum period in each phase so that these periods can be independently adjusted. The charging circuit effective in cam shaft position 1, the A phase go signal display position, starts at D. C. plus power and includes variable resistance AM, wire 35 leading to contacts *bd4* and *cd4* which are connected in parallel, thence thru wire 36 to contact *C26* and wire 37 to condenser QB, thence to D. C. negative power.

50 Cam contact *C26* is closed in cam shaft position 1, hence if there is an automatic call due to normal reversion or a traffic call for the right of way in either phase B or phase C the maximum timer charging circuit will be completed thru contact *bd4* or *cd4*. When condenser QB is charged to the breakdown voltage of tube FB 55 it will discharge thru tube FB, the coil of relay BS thence thru wires 38 and 39 to condenser QB. Relay BS will thereupon operate.

It can be seen from the foregoing discussion 60 of the vehicle interval timer circuit and the maximum timer circuit, that neither of these timers can operate to move the cam shaft out of a go signal position unless traffic in another phase or an adjustment for automatic reversion thereto 65 requires the transfer of the right of way. Hence, in the absence of any call for the right of way on another phase, the cam shaft will remain in positions 1, 3, or 5, with right of way accorded to phase A, B, or C respectively, until a right of 70 way call occurs on another phase.

The operation of either the vehicle interval timer or the maximum timer in response to such a call when the cam shaft is in position 1 will cause it to move into position 2, the phase A warning signal position. The vehicle interval timer accomplishes this thru closure of contact *cs1* of relay CS which closure completes a circuit from negative A. C. power thru wire 39, contact *cs1* to solenoid S thence to A. C. plus power. The solenoid will thereupon be energized and its core 10 will be drawn in. At the end of the solenoid stroke contact *s1* will be closed to complete a discharge circuit for condenser QA including wires 25, 26 and 27 and resistance RA. Relay CS will thereupon be deenergized thus opening contact *cs1* which will deenergize the solenoid coil. The solenoid core will then return to its unoperated position and, in so doing, move the cam shaft into position 2.

If conditions are such that the maximum timer operates it will complete the solenoid coil circuit by closure of contact *bs4* of relay BS thus energizing the solenoid and causing its core to be drawn in. At the end of the solenoid stroke contact *s2* will be closed thereby discharging condenser QB of the maximum timer thru wires 39, 38, 40 and 41 and resistance RB, whereupon relay BS will be deenergized and will open contact *bs4* thus deenergizing the solenoid the core of which will return to its unoperated position and in so doing move the cam shaft into position 2.

It has been stated that the maximum timer automatically puts in a call for the return of the right of way to a lane when it acts to terminate a right of way period thereon. With respect to 35 phase A this automatic return call is put in by operation of relay AD which is accomplished as follows.

When relay BS of the maximum timer operates it closes contact *bs1* which, with the cam shaft in position 1, completes a circuit energizing relay AD. This circuit starts at negative A. C. power and includes wire 42, contact *j5*, cam contact *C8*, contact *bs1*, to coil of relay AD thence thru wire 44 to A. C. plus power. This circuit will be complete since relay J is, as has been explained, deenergized under the prevailing conditions. Contact *j5* is therefore closed. Also cam contact *C8* is closed in cam shaft position 1, thus completing the above described circuit.

The opening of contact *bs1* as the solenoid returns to its unoperated position will open this circuit but relay AD will continue to be energized thru a holding circuit starting at negative 55 A. C. power and including wire 45, contact *iv13* of relay IV, wire 46, contact *ad1*, the coil of relay AD, and wire 44 which connects to A. C. plus power. It will be noted that in the above described holding circuit contact *iv13* is paralleled 60 by cam contact *C15* which is closed in cam shaft positions 3, 4 and 5. This circuit will therefore remain complete to keep relay AD energized until the next phase A vehicle interval period starts.

At the beginning of the phase A vehicle interval, as explained before, relay IV is deenergized thus opening contact *iv13*. Since contact *C15* is open during the A phase go signal period this holding circuit will become incomplete and thus cause relay AD to be responsive to actuation of the A phase detector during the vehicle interval portion of the phase A go signal period.

When the cam shaft solenoid is energized by either the vehicle interval timer or the maximum 75

5 timer preparatory to moving the cam shaft from position 1, the phase A go signal display position, into position 2, the phase A warning signal position, relay IV is energized by closure of solenoid 10 contact s3 which completes a circuit from negative A. C. power thru wire 42, to contact s3, wire 28 to the coil of relay IV thence to A. C. positive power. Upon operation, relay IV completes a holding circuit for itself from negative A. C. 15 power thru wire 47 to contact as3, wire 28 to contact iv1 to the coil of relay IV thence to positive A. C. power.

The operation of relay IV closes contact iv13 thereby preparing the previously described holding circuit for relay AD which will keep relay AD energized if it is operated thru action of the maximum timer relay BS at this time or if it is subsequently operated thru an actuation of the A phase detector.

20 Furthermore, while the solenoid is energized contacts s1 and s2 are both closed thereby completing the discharge circuits for condensers QA and QB respectively thru resistances RA and RB, thereby deenergizing the relay, either BS or 25 CS, a contact of which is completing the solenoid energizing circuit previously traced and preparing these condensers for use in timing new intervals.

As the cam shaft enters position 2 the A phase 30 go signal AGS is extinguished and the A phase warning signal AYS is energized. Other signal changes which occur as the cam shaft enters position 2 depend upon whether the right of way has been called to the B phase or to the C phase, but if, as assumed, the right of way is to be accorded next to the B phase, the B phase stop signal BRS is extinguished and the B phase warning signal BYS is energized as the cam shaft moves into position 2. Under the above circumstances no signal change occurs in the C or D phase at this time. With respect to relays the following conditions prevail.

35 Relay J will not be energized as has been previously explained. Relay AG, which was energized in position 1 thru a previously described circuit, will remain operated in position 2 since contact C7 is closed in both of these cam shaft positions and contact j9 remains closed due to the fact that relay J remains unoperated.

40 Relay AY will be energized, when the cam shaft has moved into position 2, thru the circuit starting at positive A. C. power and including wire 48, the coil of relay AY, wire 49, contact C24, wire 50, contact j6 of relay J which, thru 45 member j7 and wire 66, connects to negative A. C. power.

45 When relay AY operates, contact ay5, which is included in one of the three previously described energizing circuits for relay J, is closed, but as 50 previously mentioned does not energize relay J because this circuit includes contact bd6 of relay BD which contact is open due to the fact that relay BD was energized to call the right of way to B phase and remains energized until the 55 vehicle interval portion of the B phase go signal period is initiated.

When the right of way is being transferred from phase A to phase B the operation of relay AY which always causes the operation of relay AYX in order to energize the A phase warning signal, also causes the operation of relay BYX in order to energize the B phase warning signal. The circuit by which relay AYX is so energized starts at negative A. C. power and includes wire 51, contact ay2, wire 52, the coil of 60

relay AYX and wire 20 which connects with positive A. C. power. The circuit by which relay BYX is energized starts at negative A. C. power and includes wire 51, armature j10 and contact j12 of relay J, contact ay4, wire 53, the coil of relay BYX and wire 20 which connects with positive A. C. power.

The operation of relay AYX extinguishes the A phase go signal AGS by disengaging armature ay1 from contact ayx3 and energizes the A phase warning signal BYS by causing armature ayx1 to engage contact ayx2.

The operation of relay BYX extinguishes the B phase stop signal BRS by disengaging armature byx1 from contact byx3 and energizes the B phase warning signal BYS by causing armature byx1 to engage with contact byx2.

The timing of the A phase warning signal period is accomplished by a timer including condenser QA, tube FA and relay CS. The charging circuit for condenser QA in this period starts at positive D. C. power and includes wire 54, contact ay7 of relay AY, which relay it will be remembered is energized in cam shaft position 2, variable resistance AW, wire 26, condenser QA 25 which connects with negative D. C. power.

The duration of this period can be regulated by adjusting variable resistance AW to regulate the period required to charge condenser QA from zero voltage up to the breakdown voltage of tube FA. When tube FA becomes conducting condenser QA energizes relay CS thru a circuit which starts at negative D. C. power and includes wire 27, condenser QA, wires 26 and 30, tube FA, cam contact C20 which is closed in this cam shaft position, wire 33, contact as2, the coil of relay CS, wire 34, and cam contact C19 which connects with negative D. C. power.

In this cam shaft position contact C31 is open to prevent condenser QA and tube FA from operating relay AS. The operation of relay CS energizes, thru a previously described circuit, the solenoid S which operates to move the cam shaft on into position 3, the B phase go signal position.

40 As the cam shaft moves into position 3 the A phase warning signal and the B phase warning signal are extinguished. The A phase stop signal and the B phase go signal are energized at this time. No signal changes occur in the C or D phases.

45 The foregoing signal display changes are brought about by the deenergization of relays AY, AYX, BYX and AG and by the energization of relay BG.

50 The circuit changes which occur as the cam shaft moves into position 3 and which cause the signal control relays to assume the above mentioned conditions are as follows. As the cam shaft moves into position 3 relay AY is deenergized thru the opening of its previously described circuit at contact C24. The holding circuit for relay AY which includes contact C30, wire 55, contact ay1 and armature j8 is open at armature j8 since relay J is unoperated as has been previously pointed out.

55 Relay AYX is deenergized thru the opening of contact ay2 and relay BYX is deenergized thru the opening of contact ay4. Relay AG is deenergized thru the opening of cam contact C1 and contact ay6 which leaves no connection from the coil of relay AG to negative A. C. power.

60 Relay BG is energized thru the closure of cam contact C9 which completes the circuit starting at negative A. C. power and including wire 51 and contact j9, wire 22, contact C9, the coil of relay 70

75

BG and wire 20 which connects with positive A. C. power.

The phase A warning signal AYS is extinguished when armature *ayx1* disengages from contact *ayx2*. The phase A stop signal ARS is energized when armature *ayx1* engages with contact *ayx3* and armature *ag1* engages with contact *ag3*. The phase B warning signal BYS is extinguished when armature *byx1* disengages from contact *byx2*. The phase B go signal BGS is energized when armature *byx1* engages with contact *byx3* and armature *bg1* engages with contact *bg3*.

The B phase go signal period is divided into an initial interval followed by the vehicle interval period just as was the phase A go signal period. The initial interval is timed by condenser QA, tube FA and relay AS which cooperate just as they did in the A phase initial interval, the only difference being that the charging circuit for condenser QA includes cam contact C4, armature *iv11*, contact *iv7* and variable resistance BI in place of the corresponding cam contact C2, armature *iv10*, contact *iv5* and variable resistance AI which were included in phase A initial interval timing circuit. This substitution is made so that the timing of the initial interval can be independently adjusted in the different phases.

At the end of the phase B initial interval relay AS operates just as it does at the end of the phase A initial interval and deenergizes relay IV by opening the relay IV holding circuit at contact *as3*.

This institutes the phase B vehicle interval period in which the vehicle interval is timed by condenser QA, tube FA, and relay CS just as they timed the phase A vehicle interval except that the charging circuit for condenser QA during the phase B vehicle interval includes contact C4, armature *iv11*, contact *iv6* and variable resistance BV in place of the corresponding phase A circuit.

Furthermore, thru the closure of contact C3 a discharge circuit for condenser QA is prepared which will be completed to discharge condenser QA thru the closure of contact *bd3* of relay BD upon actuation of the B phase detector by which detector it will be remembered relay BD may be energized. The above circuit starts at negative power and includes wire 55, contact *bd3*, wire 56, contact C3 thence to contact *iv6*, armature *iv11*, contact C4, wire 26 to condenser QA thence back to negative power by wire 21. This is the means by which the B phase traffic extends the B phase go signal period.

When, in the absence of further B phase traffic, condenser QA charges to the breakdown voltage of tube FA, this tube will become conducting and complete the previously described circuit between condenser QA and relay CS which includes tube FA, armature *iv16*, contact *iv3*, wire 33 and contact *as2*. If there were no call for the right of way on either the A or C phase, relays AD and CD being consequently deenergized, there would be no circuit from the coil of relay CS to negative A. C. power, each one of the four possible circuits previously traced being open at some point, one of them open at contact *ad2*, another at *cd2*, a third open at contact *C17* and the fourth open at contact *C19*. Hence, relay CS would not operate and the right of way would remain on the B phase until a call to another phase completes one of the above described circuits which would permit condenser QA to discharge thru relay CS and operate the same to move the cam

shaft into position 4. However, inasmuch as it has been assumed that traffic is approaching in all the lanes including phase C the relay CS energizing circuit including contacts *cd2* and *C14* will be completed when tube FA becomes conducting at which time relay CS will therefore operate and energize the solenoid S to move the cam shaft on into position 4, the phase B warning signal position.

The maximum timer functions during the phase B vehicle interval period just as it does during the phase A vehicle interval period which has been described. If there is no call for the right of way on another phase the charging circuit for condenser QB of this timer will be incomplete since both contacts *ad5* and *cd5* in the circuit effective in cam shaft position 3 will be open.

The maximum timer condenser charging circuit for phase B includes contact C27, contacts *ad5* and *cd5* connected in parallel, wire 57 and variable resistance BM in place of the charging circuit of this timer during the A phase vehicle interval period.

A call for the right of way on the A phase will start the timing of the maximum period thru completing this charging circuit at contact *ad5*. A phase C call for the right of way will do the same thru closure of contact *cd5*.

If the maximum timer relay BS operates it moves the cam shaft into position 4 just as it moved it into position 2 which operation has previously been described. Moreover, the operation of the maximum timer in cam shaft position 3 automatically puts in a call for the return of the right of way to phase B thru energizing relay BD due to the closure of contact *bs2* just as in cam shaft position 1 is energized relay AD thru closure of contact *bs1*. The closure of contact *bs2* completes an operating circuit for relay BD which includes wire 44, relay BD, contacts *bs2* and C10, wire 43, contact *j5*, wire 42.

The signal changes which occur as the cam shaft moves into the B phase warning signal position 4 depend upon whether the right of way has been called to phase A or phase C. Since in the present portion of the description it is assumed that the right of way is next to be accorded to the C phase, the following signal display changes will occur, as the cam shaft enters position 4:

The B phase go signal BGS, the D phase go signal DGS, and the C phase stop signal CRS will be extinguished. The D phase traffic must be stopped, it will be remembered, when the C phase traffic is to be given the right of way. In addition to the above changes, the B phase warning signal BYS, the C phase warning signal CYS, and the D phase warning signal DYS are energized in cam shaft position 4 when the right of way is being transferred from phase B to phase C. To bring about the above changes in signal display in this cam shaft position relays BY, BYX and CYX will be energized.

Relay BY will be energized thru the closure of contact C22 which completes a circuit starting at positive A. C. power and including wire 48, the coil of relay BY, wire 58, contact C22, wire 59, contact *j6* and member *j1* of relay J which connects to negative A. C. power. The consequent operation of relay BY causes the completion of circuits energizing relays BYX and CYX as follows:

Relay BYX is energized thru the closure of contact *by2* which completes the circuit start- 75

ing at positive A. C. power and including wire 28, the coil of relay BYX, wire 53, contact by2 and wire 51, which connects with negative A. C. power.

5 Relay CYX is energized thru the closure of contact by4 which completes the circuit starting at positive A. C. power and including wire 28, the coil of relay CYX, wire 60, contact by4, contact j12 and armature j10 of relay J which connects with negative A. C. power.

The B phase go signal BGS is extinguished by the separation of armature byx1 from contact byx3. The B phase warning signal BYS is energized by the engaging of armature byx1 with contact byx2. The C phase warning signal CYS and the D phase warning signal DYS are energized by the engaging of armature cyx1 with contact cyx2. The C phase go signal CGS and the D phase stop signal DRS are extinguished by the separation of armature cyx1 from contact cyx2. No signal changes occur in the A phase.

The B phase warning signal period is timed by condenser QA, tube FA and relay CS which cooperate to do this just as they timed the A phase warning signal period. The charging circuit for condenser QA in the B phase warning signal period however, includes variable resistance BW and contact by1 which contact is closed upon the previously mentioned operation of relay BY.

30 At the end of the B phase warning signal period relay CS will operate as it does at the end of the A phase warning signal period. This will cause the solenoid S to move the cam shaft into position 5, the phase C go signal position.

35 As the cam shaft moves into position 5 relay BY will be deenergized by the opening of contact C22 which is included in the previously traced energizing circuit for this relay. The deenergization of relay BY will open the previously traced energizing circuits for relays BYX and CYX at contacts by2 and by4 respectively.

In addition to the above changes relay BG will be deenergized thru the opening of contact C9 since its holding circuit also is open at contact by6, and relay CG will be energized thru the closure of contact C11 which completes the circuit including wire 51, contact j9, wire 22, contact C11, coil of relay CG and wire 20.

The above outlined changes in relay position 50 cause signal display changes as follows. The B phase stop signal BRS is energized by the engaging of armature byx1 with contact byx3 and the engaging of armature by1 with contact by3. The phase B warning signal BYS is deenergized thru the separation of armature byx1 from contact byx2. The phase C warning signal CYS and the D phase warning signal DYS are deenergized by the separation of armature cyx1 from contact cyx2. The phase C go signal CGS and the phase 55 D stop signal DRS are energized by the engaging of armature cyx1 with contact cyx3 and the engaging of armature cg1 with contact cg3.

The C phase go signal period in position 5 is similar to the corresponding periods for A and B 60 phases and is comprised of an initial interval and vehicle interval which are timed by condenser QA and tube FA in the manner described above for the A and B phases. The charging resistance for the initial interval portion is variable resistor CI, and for the vehicle interval, resistor CV. Maximum timing condenser QB is charged thru a corresponding appropriate circuit including resistor CM.

If at the termination of the vehicle interval 65 timer period there were no call for transfer of

right of way from C phase to one of the other phases, none of the described circuits from relay CS coil to negative would be completed and relay CS consequently would not operate to advance the cam shaft from position 5 until such a call should be received. In the present portion of this description however, it is assumed that there is traffic in all the lanes and that relay AD is energized. Accordingly, either upon operation of relay CS by completion of the vehicle interval timer 10 period or upon operation of relay BS by completion of the maximum timer period the solenoid is advanced to position 6, the phase C warning signal period.

As the cam shaft moves into position 6 the 15 phase C go signal CGS and the phase D stop signal DRS are extinguished. Substantially simultaneously the C phase and the D phase warning signals CYS and DYS are energized and, assuming that the right of way has been called to the 20 A phase, the A phase warning signal AYS will be energized. These signal display changes are brought about by the energization of relays CY, CYX and AYX.

Relay CY is energized due to the closure of contact C23 which completes a circuit starting at positive A. C. power and including wire 48, the coil of relay CY, wire 62, contact C23, wire 63, contact j6 and contact armature j7 of relay J which connects with negative A. C. power.

The operation of relay CY causes the energization of relays CYX and AYX. The circuit for relay CYX starts at positive A. C. power and includes wire 28, the coil of relay CYX, wire 60, contact cy2, and wire 51, which connects with negative A. C. power. The circuit thru which relay AYX is energized starts at positive A. C. power and includes wire 20, the coil of relay AYX, wire 52, contact cy4, contact j12 and armature j10 of relay J, which connects with negative A. C. power. Relay CG remains energized in cam shaft position 6 thru the same circuit which energized it in position 5.

The changes in signal display as the cam shaft enters position 6 are brought about as follows: 45 The A phase stop signal ARS is deenergized by the disengaging of armature ayx1 from contact ayx3. The A phase warning signal AYS is energized by the engagement of armature ayx1 with contact ayx2.

The C phase go signal CGS and the D phase stop signal DRS are deenergized by the separation of armature cyx1 from contact cyx3. The C phase and the D phase warning signals CYS and DYS are energized by the engagement of armature cyx1 with contact cyx2.

The C phase warning signal period is timed by condenser QA, tube FA, and relay CS which cooperate just as was previously described in the discussion of the A and B phase warning signal 60 periods except that a different charging circuit is arranged for condenser QA so that the C phase warning signal period can be timed independently of the other two. This circuit is completed to begin the timing of the C phase warning period 65 as the cam shaft moves into position 6.

The operation of relay CYR, which as mentioned, takes place at this time, completes the phase C warning signal period timing circuit by closure of contact cy1, thereby completing the 70 condenser QA charging circuit which starts at positive D. C. power and includes contact cy7, variable resistance CW, wire 26, condenser QA and wire 21, which connects with negative D. C. power. The timing of the phase C warning sig- 75

nal is adjustable thru the regulation of variable resistance CW.

When the phase C warning period is over relay CS operates in accordance with previous explanation and causes the solenoid to move the cam shaft into position 1, the phase A go signal position. As the cam shaft enters position 1 relay CY is deenergized by the opening of contact C23. The deenergization of relay CY causes the opening of contacts cy2 and cy4 which cause the deenergization of relay CYX and AYX, the circuits of each of which includes one of these contacts. Relay CG is deenergized by the opening of contact C11 and relay AG is energized by closure of contact C1.

The above mentioned changes in relay positions extinguish the A phase, C phase and D phase warning signals, the circuits for which have previously been traced. In addition, the C phase stop signal, the A phase go signal and the D phase go signal are energized which returns the system to the condition prevailing at the beginning of this step by step description.

It has been previously stated that if there is no call for the right of way registered in the phase next in the normal order of progression and there is a call for the right of way in the phase not next in the normal order of progression, this equipment will operate to transfer the right of way to the phase not next in the normal order of progression without any signal display change in the omitted phase.

Operation of the system to transfer the right of way from phase A directly to phase C in response to a call for the right of way therefrom without any signal display change in phase B wherein no right of way call has been registered will now be described.

Assume that the right of way has just been accorded to phase A, cam shaft in position 1, that there is no call for the right of way in phase B and that there is such a call in phase C. Relay BD will not be energized due to the absence of a phase B right of way call. Relay CD, having been energized when the right of way was called to phase C, will still be energized thru its holding circuit which includes contact cd1 and C13.

The A phase go signal AGS and the D phase go signal DGS are energized. The B and C phase stop signals BRS and CRS are also energized. The circuit condition prevailing to bring about the above signal display combination is identical with that explained in a previous consideration of the phase A go signal period.

At the end of the phase A initial interval relay AS of the initial interval timer will operate to terminate this interval and to start the phase A vehicle interval exactly as described in the explanation previously given in connection with the transfer of the right of way from phase A to phase B.

The phase A vehicle interval is timed as has been also previously explained. The particular circuit effective to supply negative D. C. power to relay CS of the vehicle interval timer under the present circumstances is that one including cam contact C14 and contact cd2 of relay CD which relay is energized due to the phase C call for the right of way.

The phase A go signal period can be terminated by action of either the vehicle interval timer or the maximum interval timer exactly as explained before. The particular circuit thru which the

maximum timer condenser QD is charged under the present circumstances includes cam contact C26 and contact cd4 of relay CD. If the phase A go signal period is terminated by the maximum timer a phase A return right of way call is automatically put in in accordance with the previously explained method.

As the cam shaft, at the end of the vehicle interval portion of the phase A go signal period is moved into position 2 relay AY is energized just as explained previously. The energization of relay AY follows at once as has also been previously explained.

Due to the fact that the phase B go signal period is to be omitted under the present circumstances relay J will be energized by the operation of relay AY. It will be remembered that relay J remained deenergized when the right of way was being transferred from phase A to phase B.

The circuit thru which relay J is energized starts at positive A. C. power and includes wire 16, the coil of relay J, wire 19, contact ay5 of relay AY, wire 18, back contact bd6 of relay BD, which relay it will be remembered is not energized, and wire 17, which connects with negative A. C. power. As soon as relay J operates contact j2 closes thus providing a path independent of contact bd6 thru which relay J will continue to be energized if a phase B traffic actuation occurs which actuation would energize relay BD thereby opening contact bd6 included in the relay J energizing circuit.

The functions of relay J, which as mentioned operates at the beginning of the warning signal period when the normally next phase go signal period is to be omitted, are as follows:

Relay J, when operated, causes the signal display changes which would normally occur in the phase being omitted to take place in the phase beyond to which phase the right of way is being transferred. It accomplishes this by changing the connections among the signal control relays as will be later explained in detail.

Relay J, when energized, completes a special charging circuit for the maximum timer condenser QB which makes this timer effective to rapidly step the cam shaft thru the positions in which the signal indications to be omitted normally occur.

Relay J, when operated, makes effective circuits to keep the several signal control relays from being disturbed while the cam shaft is being rapidly stepped thru positions in which these relays would normally change from an energized condition to one of deenergization or vice versa.

Furthermore, relay J, when operated, opens the automatic return call circuit associated with the maximum timer so that this timer will not put in an automatic right of way call for the phase being omitted when, operating as the special rapid stepping timer, it moves the cam shaft out of the position wherein the go signal normally is displayed to the omitted phase.

The first of the four mentioned functions of relay J, that of causing the warning signal to be displayed in the phase beyond instead of in the phase normally next in the order of progression in which phase the go signal period is to be omitted, is accomplished by circuits including armature j10.

With respect to the present specific case where in the right of way is to be transferred from phase A to phase C this is brought about as follows: The operation of relay J separates armature j10 71

from contact *j12* thereby opening the previously traced circuit over contact *j12* by which relay AY, upon operation normally energizes relay BYX which in turn energizes the phase B warning signal. Hence relay BYX will not operate under the prevailing circumstances and consequently the phase B warning signal BYS will not be energized. The engagement of armature *j10* with contact *j11* completes another circuit by which relay CYX is energized when relay AY is operated. This circuit starts at negative A. C. power and includes wire 51, armature *j10*, contact *j11*, contact *ay8*, the coil of relay CYX and wire 20, which connects with A. C. positive power.

15 The energization of relay CYX causes the energization of the phase C and the phase D warning signals CYS and DYS thru a circuit previously traced. Hence the warning signal in the omitted phase, phase B in this case, is not energized but 20 the warning signal in the phase beyond, phase C in this case, is energized simultaneously with the phase A warning signal.

The second of the four mentioned functions of relay J, that of completing a special low resistance charging circuit for condenser QB of the maximum timer is accomplished by closure of contact *j4* which, with relay AY operated as is now the case, completes the circuit starting at positive D. C. power and including contact *j4*, 30 low resistance JR, wire 64, contact *ay8*, wire 65, contact C27, wire 31, condenser QB, which is connected to negative D. C. power. Thru this circuit condenser QB of the maximum timer will be charged in a short period, on the order of one 35 fourth of a second, to the breakdown voltage of tube FB whereupon relay BS will operate and cause the solenoid to move the cam shaft into position 3. While the solenoid is operated to accomplish this cam shaft movement, contact *s2* 40 closes discharging condenser QB, thus causing relay BS to be deenergized and so permitting the solenoid to return to its unoperated condition during which movement, as previously pointed out, it moves the cam shaft into position 3.

45 Condenser QB is immediately recharged thru the special low resistance charging circuit and consequently the cam shaft is moved on into position 4 by the maximum timer relay about one quarter of a second after it was moved into position 3. In cam shaft position 4 this special low resistance charging circuit for condenser QB is 50 made incomplete at contact C27 which opens in this cam shaft position.

As the cam shaft moves into position 4 the 55 warning signal period timer comprising condenser QA, tube FA and relay CS begins to time the normal phase A warning signal period at the end of which the cam shaft will be moved into position 5, the phase C go signal position, in the 60 usual manner which has been previously described.

The third mentioned function of relay J, that of preventing the signal control relays from being disturbed while the cam shaft is being stepped rapidly thru the phase B go signal position, requires that during this transition period relays J, AG, AY, AYX, and CYX which would normally become deenergized in cam shaft position 3 be kept energized until the cam shaft moves into the 70 phase C go signal position 5. This is accomplished by special holding circuits which are completed by contacts of relay J when that relay operates as will now be explained.

75 The holding circuits of every one of the above mentioned relays will remain complete so long as

relay AY remains operated, hence relay AY is the determining factor in the situation. Relay AY, it will be remembered, operates upon closure of cam contact C24 as the cam shaft moves into position 2. The operation of relay J follows 5 by closure of contact *ay5* as has been explained.

The above mentioned operation of relay J completed a holding circuit for relay AY which starts at negative A. C. power and includes wire 66, contact *j1* and armature *j8* of relay J, wire 61, contact *ay1*, wire 55, cam contact C30, wire 49, the coil of relay AY and wire 48 which connects with A. C. positive power. It will be noted that contacts *j6* and *j1*, the first of which is included in the operating circuit of relay AY and the second of which is included in the holding circuit of relay AY, are both associated with a common armature *j8* in such a way that the holding circuit of relay AY is invariably completed before the operating circuit thereof is broken. This arrangement provides that relay AY, which operates before relay J, shall not be deenergized when relay J operates.

The described holding circuit for relay AY remains complete until the opening of cam contact C30 as the cam shaft enters position 5. From the foregoing it can be seen that relays AY and J will remain energized until the cam shaft reaches position 5, the phase C go signal position. Relays AYX and CYX, of which the energizing circuits have been traced, will remain energized as long as relays AY and J remain operated, i. e., until the cam shaft reaches position 5, because contacts of relays AY and J control the energizing circuit of relays AYX and CYX.

35 Relay AG, which is energized in cam shaft positions 1 and 2 and which normally is deenergized in cam shaft position 3, will, under the prevailing circumstances remain energized until the cam shaft reaches position 5, power for this relay being supplied thru a holding circuit therefor which circuit includes contact *ay5* of relay AY, which is energized until position 5 is reached.

The fact that relay AG remains energized in cam shaft positions 3 and 4 is of no significance 45 with the apparatus adapted as shown in Fig. 3, to give the signal sequence G, A, R, A, G. However, with the apparatus adapted to give the signal sequence G, A, R, R, G, as shown in Fig. 4, the energization of relay AG in cam shaft positions 3 and 50 4, as described above, has a significance which will be pointed out later when the adaptation of the apparatus to give the G, A, R, R, G signal sequence is considered.

In addition to the foregoing, a further necessary function of relay J is to prevent the energization of relay BG which normally occurs when the cam shaft is in positions 3 and 4, which energization would cause the display of the phase B go signal in cam shaft position 3. The operation 60 of relay J prevents relay BG from operating by opening the previously traced energizing circuit for the latter at contact *j9*.

The fourth mentioned function of relay J, that of preventing the setting up of an automatic call 65 for the return of the right of way to the B phase as the cam shaft is moved out of position 3 by the maximum timer acting as a special rapid stepping timer.

This is accomplished by the opening of the 70 previously traced automatic recall circuit at contact *j5* of relay J which relay it will be remembered is operated under the prevailing circumstances while the cam shaft is in position 3.

From the above discussed circuit operation it 75

can be seen that, when the right of way is to be transferred from phase A to phase C, the cam shaft, when the phase A go signal period is over, will be rapidly stepped thru positions 2 and 3 and will then remain for a normal phase A warning signal period, timed by the phase A warning signal period timer, in cam shaft position 4, at the end of which period the cam shaft will be moved on into position 5 wherein the go signal 10 is displayed in phase C and the stop signal is displayed in all other phases.

While the cam shaft is in positions 2, 3 and 4, as above mentioned relays AY, J, AG, AYX and CYX will all be energized. The signal display 15 during this period will consequently be as follows:

The phase A warning signal AYS will be energized by engagement of armature *ayx1* with contact *ayx2*.

The phase C and the phase D warning signals 20 CYS and DYS will be energized by the engagement of armature *cyx1* with contact *cyx2*.

The phase B stop signal BRS will remain energized thru its previously traced circuit inasmuch as relays BYX and BG are both deener- 25 gized as explained above.

When the cam shaft reaches position 4, as previously mentioned the normal phase A warning signal timer times a normal phase A warning signal period at the end of which the cam shaft in 30 the usual way is moved on into position 5. As the cam shaft enters this position relay AY is deenergized thru the opening of its holding circuit at contact C30. This causes the deenergization of relays J, AG, AYX, CYX, all of which relays depended, as has been explained, upon relay AY contacts for their energy. This change completes the transfer of the right of way from phase A directly to phase C.

The operation of the apparatus to transfer the 40 right of way from phase B directly to phase A omitting phase C which operation is similar to that just described in connection with the transfer of the right of way directly from phase A to phase C, will now be explained briefly.

Assume that, while the go signal is being displayed in phase B, the right of way is called to phase A and there is no call for the right of way on phase C. Under this condition the transfer of the right of way from phase B to phase A, 50 with no signal display changes in phase C or D, will be accomplished as follows.

The movement of the cam shaft from position 3, the B phase go signal position, to position 4, the B phase warning signal position, will be occasioned by the normal operation of either the vehicle interval timer or the maximum interval timer exactly as previously described.

As the cam shaft moves into position 4 relay BY will be energized due to the completion of its 60 previously described operating circuit by closure of contact C22. Relay J will thereupon be energized by closure of contact *by5* which completes the circuit including the said contact *by5* and contact *cd6*, the last named contact being closed because relay CD is not energized, there having been no phase C right of way call to energize relay CD.

The closure of contact *j3* which parallels contact *cd6* will prevent relay J from being deenergized by a subsequent phase C right of way call, just as contact *j2* similarly provided protection for this relay against deenergization by B phase traffic actuators when the right of way was being transferred from phase A to phase C.

75 The operation of relay J completes a low re-

sistance charging circuit for the maximum timer condenser QB similar to that described in connection with the transfer of the right of way from phase A directly to phase C.

This circuit which includes contact *j4*, low resistance JR, wire 68, contact *by8*, wire 69, cam contact C25 and wire 31, remains intact in cam shaft positions 4 and 5 and so causes the maximum timer to operate to move the cam shaft out of each of these positions about one quarter 10 of a second after its entrance therein. As the cam shaft moves into position 6 this special low resistance charging circuit is rendered incomplete thru the opening of contact C25 and is therefore not effective to cause the cam shaft to 15 be moved out of position 6.

The previously described circuit thru which the operation of the maximum timer in cam shaft position 5 would normally energize relay BD in order to put in a call for the return of the right 20 of way to phase B is open due to the opening of contact *j5*. Therefore no such return call is put in under the prevailing circumstances when the maximum timer relay CS operates to move the cam shaft out of position 5.

The operation of relay J also completes a holding circuit for relay BY similar to the holding circuit previously described in connection with relay AY. This holding circuit for relay BY includes cam contact C28, contact *by1*, armature 30 *j8* and contact *j7*, and will remain intact in cam shaft positions 4, 5 and 6, thus insuring that relay BY and also the signal display control relays, BG, BYX and AYX, which under the prevailing circumstances are energized thru contacts of relay BY will remain energized continuously from the entrance of the cam shaft into position 4 until it leaves position 6, the phase C warning signal position.

The circuit thru which relay BYX is energized 40 as mentioned above, has been previously described. It includes contact *by2* of relay BY. The circuit thru which relay AYX is energized as mentioned above, includes contact *by3*, contact *j11* and armature *j10* of relay J.

Relay BG is maintained energized in cam shaft positions 5 and 6 by closure of contact *by6* of relay BY. This continued energization of relay BG has no significance with the apparatus adapted to give a signal sequence G, A, R, 50 A, G, which adaptation is now being considered. It does, however, have a significance if the apparatus is adapted to give the signal sequence G, A, R, R, G which will be pointed out later when the adaptation of the apparatus to give 55 the latter signal sequence is considered.

Due to the fact that relays AYX and BYX under the prevailing circumstances are energized in cam shaft positions 4, 5 and 6, the A and B phase warning signals AYS and BYS, the circuits for which have previously been traced, will both be energized continuously from the time the cam shaft enters the B phase warning signal position 4 until it leaves position 6, the C phase warning signal position.

The C phase go signal CGS which is normally energized when the cam shaft is in position 5, will not under the prevailing circumstances be energized while the cam shaft is in position 5 since relay CG, a contact of which is included 70 in the phase C go signal circuit, will not be energized. Relay CG will not be energized due to the opening of contact *j9*, which is included in its previously traced energizing circuit.

The C phase and D phase warning signals 75

which are normally energized when the cam shaft is in position 6 will not be so energized under the prevailing circumstances because relay CYX will not be energized, all three circuits thru which this relay could be energized being open. The circuit thru which relay CYX is normally energized in cam shaft position 6 which circuit includes contact *cy2* of relay CY is open at this contact since relay CY is not energized under the prevailing circumstances. The previously traced circuit thru which relay CY is normally energized in cam shaft position 6 is open due to the separation of contact *j6* from contact *j1*. Also, the previously traced circuit thru which closure of contact *by4* of relay BY could energize relay CYX is open due to the separation of armature *j10* from contact *j12*. The only other circuit thru which relay CYX could be energized is open at contact *ay3* since relay AY is not energized during the transfer of the right of way from phase B to phase A. Therefore relay CYX is not energized and the phase C and D warning signals are consequently not energized as was mentioned.

25 The fact that relays CG AND CYX do not operate causes the C phase stop signal CRS, the circuit of which has been traced, to remain energized continuously while the right of way is being transferred from phase B directly to phase A.

30 The cam shaft will remain in position 6 for the normal B phase warning signal period timed by the B phase warning signal period timer the circuit for which has been previously described, which circuit includes tube FA, condenser QA, 35 charging resistance BW and relay CS. This timer is made effective to time this period in cam shaft position 6 thru the closure of contacts *by1*, *C20*, *as2*, and *C19*.

When the cam shaft is moved from position 6 to position 1 by action of the phase B warning signal timer as mentioned, the described holding circuit for relay BY will be opened at cam contact C28. Relay BY will thereupon be deenergized and will cause relays BG, AYX, BYX, and 45 J to be deenergized thru the opening of contacts *by6*, *by3*, *by2*, and *by5* respectively.

The phase A and phase B warning signals AYS and BYS and the phase A stop signal ARS are thereby extinguished and the phase A go signal 50 AGS is energized in accordance with the previously described condition normally prevailing when the cam shaft is in position 1, the phase A go signal position.

If, when the right of way is accorded to phase 55 C there is a call for the right of way on phase B and no call for the right of way on phase A, the right of way will be transferred directly from phase C to phase B, the stop signal remaining continuously displayed to A phase traffic.

60 The cam shaft under the above circumstances will be moved out of position 5, the C phase go signal position, by normal action of either the vehicle interval timer or the maximum timer which has been previously explained.

65 As the cam shaft enters position 6, the C phase warning signal position, relay CY is energized as previously explained. Relay J thereupon operates being energized thru the circuit including contacts *cy5* and *ad6*, the latter contact being closed since 70 there has been no phase A right of way call to operate relay AD. Contact *j1* closes in order to protect relay J against deenergization by subsequent phase A traffic actuations which would open contact *ad6*.

75 The operation of relay J completes a holding

circuit for relay CY thru the engaging of armature *j8* with contact *j7*. This holding circuit includes contact *j1*, armature *j8*, wire *61*, contact *cy1*, and cam contact C29. It will be remembered that the association of armature *j8* with contacts *j6* and *j7* is such that the holding circuit for relay CY will be completed before the operating circuit for this relay is broken. Relay CY will therefore remain energized thru this holding circuit while the cam shaft is in positions 6, 1 and 2, being deenergized when cam contact C29 opens which occurs as the cam shaft moves into the B phase go signal position 3.

Relay CG is held energized in cam shaft positions 1 and 2 thru contact *cy6* of relay CY. This has no present significance but is significant with the apparatus adapted to give the G, A, R, R, G signal sequence which will later be pointed out.

Relay CYX is energized by closure of contact *cy2* of relay CY. This causes the extinguishing of the C phase go signal CGX, the D phase stop signal DRS and energizes the C and D phase warning signals CYS and DYS, the circuits for all of which have previously been traced.

Relay BYX is energized by closure of contact *cy3* of relay CY and the engaging of armature *j10* with contact *j11*. The operation of relay BYX extinguishes the B phase stop signal BRS and energizes the B phase warning signal BYS the circuits for which have been previously traced.

Since relays J, CG, BYX and CYX are all energized thru circuits dependent upon contacts of relay CY, these relays will all remain energized until relay CY is deenergized, i. e., until the cam shaft moves into position 3. The signals mentioned above, which are controlled by these relays, will therefore remain displayed continuously until the cam shaft reaches position 3.

While the cam shaft is in positions 1 and 2, relay AG would normally be energized. However, under the prevailing conditions, relay J being energized, contact *j9* will be open thereby rendering incomplete the previously traced circuit thru which relay AG would normally be energized. Relay AG will therefore remain unoperated throughout the transfer of the right of way from phase C to phase B.

Relay AY which would normally be energized in cam shaft position 2, the A phase warning signal position, will not be so energized under the prevailing circumstances since its previously traced operating circuit is open at contact *j6*.

Relay AYX will not be energized since one energizing circuit therefor is open at contact *ay2*, another energizing circuit therefor is open at contact *by3*, of relay BY which relay is not energized during the transfer of the right of way from phase C to phase B. The third circuit thru which relay AYX could be energized is open at contact *j12*.

No change will therefore be made in the A phase signal display since relays AG and AYX which control the A phase signals have been shown to remain continuously deenergized throughout the transfer of the right of way from phase C to phase B.

The operation of relays CY and J as the cam shaft enters position 6 also completes a low resistance charging circuit for condenser QB of the maximum timer which circuit includes contact *j4*, contact *cy8* and cam contact C26.

This circuit remains complete in cam shaft positions 6 and 1 and will therefore cause the maximum timer to move the cam shaft out of positions 6 and 1 about one fourth of a second after it enters them. In cam shaft position 2 contact *C26*

- of this circuit is open, thus rendering the maximum timer ineffective as a quick acting timer to move the cam shaft out of this position.
- Moreover, the operation of relay J causes contact *j5* to open, thereby preventing relay BD from being energized by the maximum timer to put in an automatic call for the return of the right of way to phase B when this timer, operating as a special quick acting timer, moves the cam shaft out of the phase A go signal position 1.
- The cam shaft will remain in position 2 for the normal phase C warning period timed by the previously discussed phase C warning signal timer which timer will be effective to do so due to the continued closure of contact *cy1* of relay CY which relay it will be remembered remains energized under the prevailing circumstances until the cam shaft enters position 3, the B phase go signal position.
- When the cam is moved into position 3 by action of the warning signal period timer the previously described holding circuit for relay CY is opened at contact *C29*. Thereupon relay CY and also relays J, CYX, AYX and CG which were energized thru contacts of relay CY will all be deenergized. In addition, relay BG will be energized thru its previously described circuit by closure of cam contact *C9* and the closure of contact *j9*.
- The warning signals in phases C, D and B will thereupon be extinguished. The stop signal in phase C, and the go signals in phases B and D will be energized. The circuits for all of these signals have been previously traced.
- The right of way is now accorded to phase B and consequently to phase D also. Further transfers of the right of way will be dependent upon the requirements of traffic and will take place in accordance with the described operation of the apparatus.
- It has been stated herein that the apparatus of the present invention is capable of being adapted by slight circuit changes to give signal sequences other than the G, A, R, A, G sequence. This is accomplished by changing the connections between the signal control relays and the signals. Figure 4 shows the signal connections which give a G, A, R, R, G signal sequence in each of the lanes.
- Both of the above mentioned signal display sequences are in common use. Hence it is shown herein how the embodiment of the present invention can be adapted to provide either one of them. Several other signal sequences can be provided by connecting the signals to the signal control relays in different ways. The two adaptations depicted herein are shown primarily in order to demonstrate the flexibility of the apparatus with respect to signal display sequence.
- Figure 4 includes the signals in the several lanes, the signal control relays AG, BG, CG, AYX, BYX, CYX and two additional relays, DG and DY, included to control the D phase signals. The energizing circuits for these relays are shown in Fig. 3 excepting those of relays DG and DY which will be discussed later. Hence the conditions under which each of these relays, except DG and DY, will be energized or deenergized, will be the same in Fig. 4 as in Fig. 3. Considering the arrangement of the relay contacts and the two supplementary relays of Fig. 4 which are connected, as indicated, to the structure of Fig. 3, the signal indications given by the apparatus as shown in Fig. 4 will be as follows:
- When the cam shaft is in position 1, the A

phase go signal position, relay AG is normally energized and relay AYX is normally deenergized as has been previously shown. Hence the phase A go signal AGS will be energized thru contact *ayx3* and armature *ayx1* of relay AYX and contact *ag2* and armature *ag1* of relay AG.

Relays BG and CG are normally deenergized when the cam shaft is in position 1 as has been explained; hence the B phase stop signal BRS is energized thru armature *bg1* and contact *bg3* and the C phase stop signal CRS is energized thru armature *cg1* and contact *cg3*.

In Fig. 4 the D phase signals are controlled by relays DG and DY. These two additional relays are needed because of the non-symmetry of the signal sequence G, A, R, R, G, which precludes the use of the phase D signal connections shown in Fig. 3.

It will be noted that relay DG is energized at all times when the phase C stop signal is energized, since its energizing circuit is connected to the positive side of the phase C stop signal circuit and includes wire *70*, the coil of relay DG and wire *71* which connects to A. C. negative power.

Relay DY is connected in parallel with relay CYX thru its circuit including the coil of relay DY and terminal *72* which connects with the relay CYX circuit in Fig. 3.

With the cam shaft in position 1 relay DG will normally be energized and relay DY will normally be deenergized. Hence the phase D go signal DGS will be energized thru its circuit which starts at positive A. C. power and includes armature *dg1*, contact *dg2*, armature *dy1*, contact *dy3*. The phase D stop signal circuit is open at contact *dg3* and the phase D warning signal circuit is open at contact *dy2*.

From the foregoing discussion, it is evident that when the cam shaft is in position 1 the go signal is normally displayed in phases A and D, whereas the stop signal is normally displayed in phases B and C.

As the cam shaft moves into position 2, the A phase warning signal position, relay AYX is energized, thereby extinguishing the A phase go signal AGS by opening its circuit at contact *ayx3* and the A phase warning signal AYS is energized by the completion of its circuit thru the engaging of armature *ayx1* with contact *ayx2*.

At the same time, as previously shown, if the right of way is next to be accorded to phase B, relay BYX will be energized. However, this change will not alter the signal display since armature *byx1* is not connected to power due to the fact that relay BG is deenergized in cam shaft position 2, which causes armature *bg1* to be separated from contact *bg2*, thereby disconnecting armature *byx1* from power.

The fact that relays BG and CG are normally deenergized in cam shaft position 2 causes the B and C phase stop signals to remain energized during the A phase warning signal period which is in accordance with the requirements of the G, A, R, R, G, signal sequence.

If, as it is now assumed, the right of way is next to be accorded to phase B, the cam shaft will, upon leaving position 2, stop in position 3, relays AYX, BYX and AG will thereupon all be deenergized and relay BG will be energized as previously explained. Therefore, in cam shaft position 3 the A phase warning signals AYS will be extinguished by the opening of its previously traced energizing circuit at contact *ayx2*. The A phase stop signal AGS will be energized due to the engaging of armature *ag1* with contact *ag3*. The B phase go

signal BG_S will be energized thru the circuit including contacts *by23* and *bg2*.

If, contrary to the above assumption, the right of way upon being withdrawn from phase A is next to be accorded to phase C, relays AYX, CYX and DY will be energized when the cam shaft moves into the position 2, the A phase warning signal positions.

The energization of relays AYX and CYX has no effect on the signal display since their armatures are not connected to power as pointed out above in the case of relay BYX. The energization of relay DY which relay as explained previously is connected in parallel with relay CYX, extinguishes the phase D go signal DGS by opening its energizing circuit at contact *dy3* and illuminates the phase D warning signal DYS by the engagement of armature *dy1* with contact *dy2* which completes the circuit starting at positive A. C. power and including armature *dg1*, contact *dg2*, armature *dy1*, contact *dy2*.

It will be remembered that when the right of way is being transferred from phase A to phase C, which case we are now considering, the cam shaft is rapidly stepped thru positions 2 and 3 into position 4 wherein it rests for the normal phase A warning signal period after which it moves on into position 5, the phase C go signal position.

It will also be remembered that the signal control relays remain in the same condition in cam shaft positions 2, 3 and 4 and until the cam shaft moves into position 5. Hence the signal display described above will remain unchanged until the cam shaft reaches position 5, the C phase go signal position.

As the cam shaft moves into the last named position relays AG, AYX, CYX and consequently relay CY which is connected in parallel with relay CYX are deenergized. At the same time relay CG is energized. All of the above changes in relay condition have been previously explained.

In consequence of these changes in relay condition the A phase warning signal AYS is extinguished by the opening of its circuit at contact *ag2* and the A phase stop signal ARS is energized by the engagement of armature *ag1* with contact *ag3*. Furthermore, the phase C warning signal CYS is deenergized by the disengaging of armature *cyr1* from contact *cyr2* and the C phase go signal CGS is energized by the engagement of armature *cyr1* with contact *cyr3* and the engagement of armature *cg1* with contact *cg2*.

The separation of armature *cg1* from contact *cg3* extinguishes the phase C stop signal CRS and deenergizes relay DG. The deenergization of relay DG extinguishes the phase D warning signal DYS by opening its circuit at contact *dg2* and energizes the phase D stop signal DRS by the engagement of armature *dg1* with contact *dg3*.

The cam shaft now rests in position 5 with the go signal displayed to phase C and the stop signal displayed in phases A, B and D.

We have now considered in detail the transfer of the right of way from phase A to phase B or phase C. The transfer of the right of way from phase B to phase C or phase A is accomplished in a similar manner which we will now consider in somewhat less detail.

When the right of way is leaving phase B and is next to be accorded to phase C, the cam shaft moves from position 3 to position 4 whereupon relays BYX, CYX and DY are energized in ac-

cordance with previous explanation. This causes the go signals to be extinguished and the warning signals to be energized in phases B and D but occasions no signal display change in phase C wherein the stop signal remains displayed in accordance with the requirements of the G, A, R, R, G signal sequence. The circuits for all of these signals have been previously traced.

At the end of the phase B warning signal period the cam shaft moves into position 5 the phase C go signal position, wherein it remains during the phase C go signal period. Relays BYX, CYX, BG, DG and DY are therefore deenergized and relay CG is energized. The circuits of all of these relays have been previously traced.

The energization or deenergization of the relays as mentioned above causes the warning signals to be extinguished, and the stop signal to be displayed, in phases B and D, and causes the go signal to be displayed in phase C. The circuit changes by which these signal changes are effected have been previously described.

We have considered above the functioning of the signal control circuits to transfer the right of way from phase B to phase C. When the right of way is to be transferred from phase B to phase A, omitting the phase C go signal display, the apparatus operates as follows:

As the cam shaft moves into position 4 relays BYX, AYX are energized and they, with relay BG, are held continuously energized while the cam shaft is stepped rapidly around to position 6 wherein it remains with the above mentioned relays continuously energized for the normal phase B warning signal period as has been explained.

During this period the phase B go signal is extinguished and the phase B warning signal is energized by the operation of relay BYX. The operation of relay AYX is of no effect as has been previously explained. The phase D signal display is not affected since neither relay DG or DY is changed.

At the end of the normal phase B warning signal period the cam shaft is moved into position 1, the phase A go signal position, whereupon relays AYX, BYX and BG are deenergized and relay AG is energized, as has been explained. This causes the phase B warning signal and the phase A stop signal to be extinguished and also causes the phase A go signal and the phase B stop signal to be energized in accordance with the previously explained operation of their circuits.

When the right of way is to be transferred from phase C to phase A, the movement of the cam shaft into position 6 causes the operation of relays CYX, DY and AYX which causes the phase C go signal to be extinguished and the phase C warning signal to be energized in accordance with the previously explained operation of their circuits. No other signal changes occur in this cam shaft position.

At the end of the phase C warning signal period the cam shaft moves into position 1, the phase A go signal position, whereupon relays CYX, DY, AYX and CG are deenergized and relays AG and DG are energized which causes the phase C warning signal, the phase D stop signal and the phase A stop signal to be deenergized and in addition causes the phase A and phase D go signals to be energized. All of the above signal display changes are made in accordance with the previously explained operation of the signal circuits.

When the right of way is to be transferred from phase C to phase B omitting the phase A

go signal display, the cam shaft upon moving into position 6 causes relays CYX, DY and BYX, to be energized and these relays, with relay CG which is normally energized in cam shaft positions 5 and 6, are held continuously energized while the cam shaft is rapidly stepped around to position 2 where it remains during a normal phase C warning signal period with relays remaining as described above.

10 The relay conditions given above cause the phase C go signal to be deenergized and the phase C warning signal to be energized with no other signal display change which is in accordance with the previously explained operation of 15 the signal circuits.

At the end of the phase C warning signal period the cam shaft moves into position 3, the phase B go signal position, whereupon relays CYX, DY, BYX and CG are deenergized and relays BG and DG are energized which causes the phase C warning signal, the phase D stop signal, and the phase B stop signal to be deenergized. In addition, the above described relay changes caused the phase B and phase D go signals to be 25 energized. All of the foregoing signal display changes are made in accordance with the previously described operation of the signal control circuits which govern these signals.

The right of way is now accorded to phase B 30 and consequently to phase D where it will remain until called to another phase either by traffic or by normal reversion thereto.

From the foregoing description, it will be appreciated that the present invention provides an 35 improved form of traffic control system of the traffic actuated type for use at intersections of more than two interfering traffic lanes and in which system the signal controller is adaptable to produce several different signal display sequences. For purposes of example there have 40 been described two such sequences in which a change or warning signal is displayed to each lane, both prior to and following the right of way period on the lane or only following such period. By simple rearrangement of the circuits and relays directly controlling the signal display many other signal display sequences may be obtained.

Although the present description shows an arrangement for producing additional flexibility from a six position cycle by providing two successively timed periods in each of the green or go signal positions, it will be appreciated that the amber positions might similarly be arranged 55 to provide two successively timed periods, for instance for facilitating the display of a double change period as green and amber, then amber. Thus the specific objects enumerated and others are achieved. It is understood that various modifications may be made without departing from the spirit of the invention as defined by the 60 claims.

I claim:

1. In a traffic control apparatus having stop, 65 go and caution signals for each of more than two intersecting traffic lanes, traffic actuated means in the respective lanes and a time controlled mechanism for operating the signals to display the signals successively in the several 70 lanes for the control of traffic in accordance with traffic actuation in such lanes, said mechanism including a switching device having a plurality of positions through which it is adapted to be operated for time periods to cause display of the 75 go signal successively to the several lanes and

stop signals to be concurrently displayed to the other lanes and intervening positions in which the caution signal for any one lane is displayed, means forming a part of said mechanism and, when said mechanism is in position displaying 5 a caution signal to one lane following display of the go signal therein and in absence of actuation of the traffic actuated means in the next following lane in the successive operation, operated to reduce substantially the time periods of the 10 positions corresponding to the go signal and caution signal for said next following lane and to prevent display of said go and caution signals and to cause display of the stop signal instead during such reduced time periods. 15

2. In a traffic control apparatus for three intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated. 30 35

3. In a traffic control apparatus for three intersecting traffic lanes comprising first, second and third lanes and having stop, go, and caution signals and traffic actuated means for the respective lanes and a time controlled switching mechanism for operating said signals in accordance 40 with traffic actuation of said means, said mechanism having a plurality of positions through which it is adapted to be operated at time periods by actuation of the several traffic actuated means, such positions including at least one for each lane 45 for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to maintain display of the stop signal in said second lane and to prevent display of said go and caution signals in said second lane in said last mentioned positions when said relay means is operated. 60 65 70

4. In a traffic control apparatus for three in- 75

intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to maintain display of the stop signal in said second lane and to prevent display of said go and caution signals in said second lane in said last mentioned positions when said relay means is operated, and including means for maintaining the traffic actuated means of the second lane actuated after any momentary actuation of the latter by traffic while said mechanism is in the last mentioned positions of said second lane to cause subsequent operation of said mechanism through the go and caution signal positions of the third and first lanes in succession to return to the go signal position of said second lane and to display said go signal therein.

5. In a traffic control apparatus for three intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such position including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means to maintain display of the stop signal in said second lane and to prevent display of said go and caution signals in said second lane in said last mentioned positions when said relay means is operated.

actuated means of the second lane actuated after any momentary actuation of the latter by traffic while said mechanism is in the last mentioned positions of said second lane to cause subsequent operation of said mechanism through the go and caution signal positions of the third and first lanes in succession to return to the go signal position of said second lane and to display said go signal therein.

7. In a traffic control apparatus for three intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means to maintain the caution signal display in said first lane throughout the last mentioned positions when said relay means is operated.

8. In a traffic control apparatus for three intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means displaying the caution signal in said third lane in said last mentioned positions when said relay means is operated to indicate to said third lane that the latter is about to have its go signal displayed. 45 50 55 60 65 70

9. In a traffic control apparatus for three intersecting streets, a signal for the third street is delayed by a time interval which is longer than the time interval for the second street but shorter than the time interval for the first street.

- secting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means displaying substantially immediately the caution signal in said third lane to indicate the latter lane is about to have its go signal displayed and maintaining the caution signals for the first and third lanes displayed concurrently while the mechanism is operated through the last mentioned positions of said second lane when said relay means is operated.
10. In a traffic control apparatus for three intersecting traffic lanes comprising first, second and third lanes and having stop, go, and caution signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means displaying substantially immediately the caution signal in said third lane to indicate the latter lane is about to have its go signal displayed and maintaining the caution signals for the first and third lanes displayed concurrently while the mechanism is operated through the last mentioned positions of said second lane when said relay means is operated.
11. In a traffic control apparatus for three intersecting traffic lanes comprising first, second and third lanes and having stop, go, and caution

signals and traffic actuated means for the respective lanes and a time controlled switching mechanism for operating said signals in accordance with traffic actuation of said means, said mechanism having a plurality of positions through which it is adapted to be operated at time periods by actuation of the several traffic actuated means, such positions including at least one for each lane for displaying the go signal to that lane and the stop signal to the other lanes and a following position for each lane for displaying the caution signal in such lane, means operated by actuation of said traffic actuated means in said third lane when said mechanism is in position displaying the go signal to said first lane to operate said mechanism into the following caution signal position for said first lane, relay means operated at the beginning of the latter caution signal position by the traffic actuated means of said second lane in absence of actuation in said second lane and maintained operated through the go and caution signal positions of said second lane, said relay means including means to reduce substantially the time period of said mechanism in said last mentioned positions when said relay means is operated, and including means to maintain display of the stop signal in said second lane and to prevent display of said go and caution signals in said second lane in said last mentioned positions when said relay means is operated, said relay means including means to maintain the caution signal display in said first lane throughout the last mentioned positions when said relay means is operated.

12. In a traffic control apparatus for the intersection of three mutually interfering traffic lanes comprising first, second and third lanes, and a fourth lane interfering only with said third lane, and having stop, go and caution signals for each of said lanes, traffic actuated means for the three mutually interfering lanes and a time controlled mechanism for operating said signals for the control of traffic, said mechanism having a plurality of positions through which it is operated to display said go signals for time periods to said first, second and third lanes successively in response to traffic actuation of the respective traffic actuated means and to omit such go signal period in any of said lanes in the absence of such traffic actuation, said mechanism including means displaying said stop signals in the other mutually interfering lanes during display of the go signal to any one of the mutually interfering lanes, means displaying said caution signal in any one lane following display of said go signal therein and prior to display of said stop signal therein upon operation of said mechanism from one position to another to change display of the go signal from such one lane to another lane in response to traffic actuation in the latter, and means displaying the go signal in said fourth lane concurrently with display of the stop signal in said third lane and displaying the stop signal in said fourth lane concurrently with display of the go signal in said third lane, relay means operated by said mechanism during display of the caution signal in said first lane only in the absence of traffic actuation on said second lane at the beginning of the last mentioned signal display to interrupt display of the go signal in said fourth lane and to display the caution signal in said fourth lane concur-

rently with the caution signal display in said first lane.

13. In a traffic control apparatus for the intersection of three mutually interfering traffic lanes comprising first, second and third lanes, and a fourth lane interfering only with said third lane, and having stop, go and caution signals for each of said lanes, traffic actuated means for the three mutually interfering lanes and a time controlled mechanism for operating said signals for the control of traffic, said mechanism having a plurality of positions through which it is operated to display said go signals for time periods to said first, second and third lanes successively in response to traffic actuation of the respective traffic actuated means and to omit such go signal period in any of said lanes in the absence of such traffic actuation, said mechanism including means displaying said stop signals in the other mutually interfering lanes during display of the go signal to any one of the mutually interfering lanes, means displaying said caution signal in any one lane following display of said go signal therein and prior to display of said stop signal therein upon operation of said mechanism from one position to another to change display of the go signal from such one lane to another lane in response to traffic actuation in the latter, and means displaying the go signal in said fourth lane currently with display of the stop signal in said third lane and displaying the stop signal in said fourth lane concurrently with display of the go signal in said third lane, relay means operated by said mechanism during display of the caution signal in said second lane and only if traffic actu-

ation in said third lane has occurred by the beginning of the last mentioned signal display to interrupt display of the go signal in said fourth lane and to display the caution signal in said fourth lane concurrently with the display of said 5 caution signal in said second lane.

14. A traffic control apparatus for more than two interfering traffic lanes including right of way signals for the respective lanes, a control mechanism operable through a cycle of time 10 periods for displaying said signals successively in the several lanes for such time periods, relay means for each lane adapted to be actuated by traffic therein, and maintained actuated after such actuation by traffic occurring when the right 15 of way signal is not displayed in its lane and until the right of way signal is displayed in its lane, means in said mechanism and operated when the right of way signal is displayed on a first of said lanes and the relay means for another of said 20 lanes is actuated to cause said mechanism to change the signal display from go on said first lane to go on the other lane, and further relay means operated by the relay means of any lane intervening between said first lane and said other 25 lane in the successive signal display of said mechanism when the latter relay means is not actuated upon such change of signal display, said further relay means including means to maintain it so operated through the time period for 30 go signal display in said intervening lane to reduce substantially the latter time period and to prevent display of the go signal to such intervening lane during such reduced time period.
